CLAIM

The ornamental design for a combined bottle and cap for cosmetics as shown and described.

DESCRIPTION

FIG. 1 is a top perspective view of a combined bottle and cap for cosmetics showing our new design;

FIG. 2 is a bottom perspective view thereof;

FIG. 3 is a top perspective view of the bottle of the combined bottle and cap for cosmetics shown separately from the cap to show aspects of the design that are not visible when combined;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a top perspective view of the cap of the combined bottle and cap for cosmetics shown separately from the bottle to show aspects of the design that are not visible when combined;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

The broken lines in the figures depict portions of the combined bottle and cap for cosmetics that form no part of the claimed design.
